UNITED STATES PATENT OFFICE.

HORATIO R. HARPER, OF NEW YORK, N. Y.

CANDLE-SHEATH.

SPECIFICATION forming part of Letters Patent No. 250,145, dated November 29, 1881.

Application filed August 16, 1881. (No model.)

To all whom it may concern:

Be it known that I, HORATIO R. HARPER, a citizen of the United States, residing in the city and county of New York, in the State of New York, have invented a new and useful Candle Sheath or Case Adapted to be Ornamented; and I do hereby declare that the following is a full, clear, and exact description thereof, and of its mode or manner of operation, which will enable others skilled in the art to which it appertains to make and use the same, reference being had to the accompanying drawings, and to the letters of reference marked thereon, which form a part of this specification.

15 My invention is illustrated in the accompanying drawings, in which Figure 1 is a vertical section of the entire sheath or case, and Fig. 2 is a perspective view of the case, decorated and disposed in a candlestick.

20 B is a tube for containing a candle and a spring for raising it, made of such size as to receive easily the candle to be used therein. The top of this tube is open, to allow the wick of the candle to project, but is finished with an inwardly-projecting shoulder, to prevent the candle being forced upwardly out of it by the spring beneath. If desired, the top of this tube B may be furnished with a cap, A, which is preferably made with a cup-shaped depression that effectually retains the melted matter of the candle and prevents any overflow thereof down the outside of the case. The sides of this cup also shield the flame, whereby a steady light is obtained. In the drawings this cap A is shown as a separate part, screwed onto the body of the tube. It may, however, be simply fitted to slide over it, as the shoulder on the tube retains the candle. This I consider the best way to make my invention when the tube B is constructed of rubber or paper, or of any material liable to be injured by the burning candle, as the cap A is preferably made of metal. If such a cap is desired on a tube made of metal, it may be made in one piece with the tube.

45 At the bottom of the sheath or case B, I attach a foot or shank, C, which is made to be adjustable, so that it may fit into any ordinary candlestick in general use. This foot or shank C consists of a plate with a rim threaded to be

screwed into the tube B, as shown in the drawings; but it may also be attached by having slots in one part and suitable bearings to engage therewith in the other part; or it may be attached in any other suitable manner that 55 will secure a firm attachment to the tube, as it is the bearing rest for the spring b, which actuates the candle in the tube. This plate may be sufficiently large to project beyond the tube, as shown at c, and form a support for a glass 60 cup, such as are generally used on candlesticks, if desired. Under this plate I fasten any suitable device that is capable of increased or diminished circumference, so that it is adjustable to fit any size of candlestick and retain the 65 sheath or case in position. The device shown answers the purpose very well. It consists of a slotted thimble, open at the bottom, made of pliable metal, as shown, having its upper circumference small enough to enter into any of 70 the smaller candlesticks in use, and by bending the metal prongs it may readily be enlarged to fit any of the larger candlesticks; but for this purpose a variety of devices may be employed, which need not be described, as they 75 can readily be made by a mechanic, the object being to enlarge or reduce the circumference of the shank or foot to make it adjustable to fit into candlesticks of varying sizes. By the addition of this foot or shank the sheath or case 80 is made a completed structure, a perfect cover and protector for the candle, independent of any candlestick, and may be used in any kind of candlestick—for the table, for bracket-lights or sconces, for candelabra, or for any use 85 to which candles may be applied.

Within the tube B is disposed a suitable spring, b, of sufficient strength to raise the candle desired to be used, having a button at its upper end upon which the candle rests. 90

To use my invention the foot C is taken off the tube B, the candle is inserted therein, and then the spring is inserted, after which the part C is again properly fastened to the tube. This case may be painted or ornamented, as 95 candles now are, and by its use the ornamentation is preserved a long time. It always stands straight in the candlestick, unlike the ornamented candles, which bend and lean in warm weather or in a warm room, and any kind of 100

candles may be used, the case always presenting a beautiful appearance.

I do not claim a candlestick with a spring for raising the candle, as that is not new; but 5 What I do claim as new, and desire to secure by Letters Patent, is—

A candle sheath or case adapted to contain a candle and a spring for raising it, consisting

of a suitable tube provided with a foot or shank capable of adjustment to candlesticks of varying sizes. 10

HORATIO R. HARPER.
